US00D983269S

(12) **United States Design Patent** (10) **Patent No.:** **US D983,269 S**
Daddar et al. (45) **Date of Patent:** **** Apr. 11, 2023**

(54) **INPUT APPARATUS FOR A GAMES CONSOLE**

(71) Applicant: **Ironburg Inventions Limited**,
Wincanton (GB)

(72) Inventors: **Sunil Daddar**, Suwanee, GA (US);
Duncan Ironmonger, Milton, GA (US);
Carl Jeffrey, Oxenton (GB)

(**) Term: **15 Years**

(21) Appl. No.: **29/738,762**

(22) Filed: **Jun. 19, 2020**

(51) **LOC (14) Cl. 21-01**

(52) **U.S. Cl.**

USPC **D21/333**

(58) **Field of Classification Search**

(57) **CLAIM**

The ornamental design for an input apparatus for a games console, as shown and described.

DESCRIPTION

FIG. 1 is a rear and bottom perspective view of a first embodiment of an input apparatus for a games console in accordance with the present design;

FIG. 2 is a rear and top perspective view thereof;

FIG. 3 is a bottom view thereof;

FIG. 4 is a top view thereof;

FIG. 5 is a left side view thereof;

FIG. 6 is a right side view thereof;

FIG. 7 is a front elevational view thereof;

FIG. 8 is a rear elevational view thereof;

FIG. 9 is a rear and bottom perspective view of a second embodiment of an input apparatus for a games console in accordance with the present design;

FIG. 10 is a rear and top perspective view thereof;

FIG. 11 is a bottom view thereof;

FIG. 12 is a top view thereof;

FIG. 13 is a left side view thereof;

FIG. 14 is a right side view thereof;

FIG. 15 is a front elevational view thereof; and,

FIG. 16 is a rear elevational view thereof.

The broken lines in the drawings show environment that forms no part of the claimed design.
